L. L. MAST

COUPLING FOR SECTIONAL RODS

Filed March 29, 1924

LOUIS L. MAST,

Edgar Thaulerkey
Attorney

Inventor

UNITED STATES PATENT OFFICE.

LOUIS L. MAST, OF WEST MILTON, OHIO.

COUPLING FOR SECTIONAL RODS.

Application filed March 29, 1924. Serial No. 702,910.

To all whom it may concern:

Be it known that I, LOUIS L. MAST, residing at West Milton, county of Miami, State of Ohio, post-office address West Milton, Ohio, citizen of the United States, have invented certain new and useful Improvements in Couplings for Sectional Rods, of which the following is a specification.

The coupling of this invention is designed more particularly for use in connection with lightning-rods.

Lightning-rods are now commonly formed from copper tubing, and, for convenience in manufacture and shipment, this tubing is made up in comparatively short sections, usually about ten feet in length. The several sections are united in endwise relation when the rod is erected and, when so united, constitute the complete lightning-rod.

The object of this invention is, in general, to improve upon the sectional-rod coupling disclosed in my United States Patent No. 1,140,052, dated May 18, 1915.

The invention is graphically portrayed in the accompanying drawing, forming part of this specification, and in which like reference characters identify corresponding structural parts throughout the several views. The different figures or views shown on the drawing may be briefly described as follows:

Figure 1 is a collective detail view, in perspective, of one section of my improved rod-coupling and of a lightning-rod section (shown broken away), showing the position of said parts before said coupling-member has been secured to said rod-section;

Figure 2 is a detail view, in perspective, of the other coupling-member;

Figure 3 is a detached detail view, in perspective, of one of the cores carried by the coupling-members;

Figure 4 is a fragmentary view, in elevation, partly in section, of the coupling-members and two lightning-rod sections, showing said parts in their partially assembled position;

Figure 5 is a fragmentary view, in elevation, of the two coupling-members of my invention in completely assembled position relative to two adjacent lightning-rod sections;

Figure 6 is a fragmentary view, in elevation, partly in section, of one of the coupling members showing the completely assembled and operative position thereof with

respect to an adjacent lightning-rod section; and

Figure 7 is a cross-sectional view taken on the plane of the section-line 7—7 appearing in Fig. 6.

My invention is shown as applied to a lightning-rod formed of metal tubing having spiral corrugations extending lengthwise thereof; but it will be understood that the invention may be used in connection with rods, or similar parts of various kinds, and that it is not necessary to the application of my coupling that the rod shall be hollow throughout its length, it being sufficient if the two rods or two sections of the rod to be connected have openings in their ends to receive the cores of the coupling-members.

The lightning-rod shown in the drawing is formed of a plurality of hollow sections. Each section consists of a length of metal tubing, preferably copper, corrugated lengthwise and spirally thereof. In the present instance, I have provided the sections of the rod with six longitudinal corrugations or ribs. I have selected this number because it enables me to so corrugate the rod as to give it the desired qualities, that is, to enable it to be bent or crimped without destroying its shape, and, at the same time, owing to the large number of corrugations produced, each corrugation or rib extends about the axis of the rod only a few times, and, therefore, the coil which these corrugations tend to form has but a few convolutions, and the effect produced by the electricity traveling about these convolutions is greatly reduced. The machine upon which these hollow rod sections are formed and corrugated is of such a character that the end portions of the corrugations are substantially straight or parallel with the axis of the rod. While this arrangement of the corrugations is preferred and is such as to facilitate the application of my invention to the rod, it is by no means essential.

The coupling which I have devised consists, broadly, of two members, having means for separably connecting the same one to the other, each section being provided with a core, of peculiar construction, adapted to extend into the open end of the rod section to which it is to be attached, and having one or more fingers arranged to bear upon the exterior of the rod section when

the core has been placed within the opening in the rod. These fingers are of such a character that they may be pressed forcibly against the outer surface of the rod, therefore 5 by crimping or distorting the metal of the rod against the core and thereby effect an interlocking connection between the core and said rod, whereby the coupling-member is clamped rigidly to the end of the rod-section.

The details of the construction may be varied; but, in the present embodiment of the invention, I have shown the coupling as comprising two members, which are preferably 15 conveniently and advantageously constructed from pure uniform seamless copper tubing, said members being identified in the drawing by the reference-numerals 2 and 3.

20 The member 2 has a screw-threaded socket 4 adapted to receive a screw-threaded nipple 5 on the coupling-member 3.

In the application of the couplings to the rod-sections 1, 1, the coupling-member 2 is 25 secured to one end of a rod-section, and the coupling-member 3 to the adjacent end of the adjoining rod-section, as shown in Fig. 5, thereby enabling the rod-sections to be 30 connected one to the other, in series, to form a continuous rod of any desired or predetermined length.

Each section of the coupling carries a core shown in detail in Fig. 3 and identified, in 35 this figure, by the reference-numeral 6. This core is of peculiar conformation, for a particular purpose. It comprises an annular head 7, a truncated cone-shaped shank 8 projecting concentrically from said head, the base or largest diameter of said shank 40 being at the head of the core, and an annular enlargement or boss 9 on the reduced end of the shank.

This core 6 is preferably made separate 45 from the coupling-sections 2 and 3, and is advantageously made of brass. The core is rigidly secured in the coupling member in any suitable or preferred manner; it may be driven into the coupling-member, so that the head 7 may have a very tight frictional fit 50 with the tubular coupling-member, or said head, when in position within the coupling-member, may be brazed to the latter, or other ways and means of securing the core 55 in the coupling-member against accidental removal may be employed, as will readily suggest themselves to any mechanic.

Each coupling-member 2 and 3 carries, at 60 one end, longitudinally-projecting fingers 10 in an annular series, arranged to be pressed forcibly against the outer surface of the rod-section 1 to clamp the same against the core 6. As here shown, these fingers are arranged substantially parallel with the core, 65 but flared slightly away therefrom, to facilitate

the application of the coupling-member to the end of the rod-section 1. These fingers are especially desirable where the coupling is to be applied to a corrugated rod section, and I prefer to employ one finger 70 for each groove formed by the corrugations of the rod. In the present instance, there are six such fingers, preferably integral with the coupling member, and capable of being bent inward and pressed against the metal 75 wall of the rod to clamp this wall into locking engagement with the core 6.

The operation and manner of use of the coupling will be apparent from the foregoing description. The coupling is applied 80 to the end of the rod-section by inserting a core in the hollow end and pressing the fingers against the outer surface of the rod with sufficient force to crimp the metal of the rod into contact with the shank 8 and the boss 9, as clearly shown in Fig. 6, thereby effecting an interlocking engagement between the core 6 of the coupling members 2, 3 and the rod section 1. This completes the 90 rod section. When the rod-sections are on the job and ready to be erected, the ends of the rod sections are brought together and the couplings screwed one into the other, thereby quickly and firmly uniting the rod, 95 and, after the rod is in position, the sections can not be separated except by beginning at one end and systematically tearing down the rod as a whole.

The advantages of my present coupling-member over that disclosed in my Patent 100 No. 1,140,052 are that I am enabled to make the coupling-members 2 and 3 out of pure uniform seamless copper tubing, and to provide brass cores 6 separable from the members 2 and 3. In the patented construction, 105 the coupling-members and the cores carried thereby are unitary structures, being made by casting, and the patented coupling-members being, in fact, not tubular bodies. As 110 the coupling member, with its integral core, of the patent had to be made by casting, in a foundry, it could not be made uniform, and could not be made in pure copper. The coupling-member of my present invention 115 presents an absolutely uniform surface of conductivity for electricity.

Having thus fully described my invention, what I claim as new and desire to secure by Letters-Patent of the United States is: 120

In a lightning-rod, the combination with two hollow lightning-rod sections, of a coupling-device therefor, comprising two sheet-metal tubular members removably secured together at adjacent ends, each provided, at its free end, with an annular series of fingers bearing against the exterior surface of the adjacent lightning-rod section, at one end thereof, a pin removably disposed 125 in the bore of each tubular member and 130

comprising a truncated cone-shaped shank, an enlarged circular base at one end of said shank snugly fitting the interior surface of the wall of the tubular member, and an enlargement on the reduced end of said shank, said fingers bent inward and the end of the lightning-rod section crimped against said

shank and under said enlargement, whereby the tubular member and lightning-rod section are interlocked with said pin. ¹⁰

In testimony whereof I hereunto affix my signature.

LOUIS L. MAST.
